UNITED STATES PATENT OFFICE.

WILLIAM HORN, OF GLENSIDE, PENNSYLVANIA, ASSIGNOR TO HORN & BRANNEN
MANUFACTURING COMPANY, A CORPORATION OF PENNSYLVANIA.

DESIGN FOR A BRACKET WALL-PLATE.

49,891.

Specification for Design.

Patented Nov. 14, 1916.

Application filed July 13, 1916. Serial No. 109,181. Term of patent 3½ years.

To all whom it may concern:

Be it known that I, WILLIAM HORN, a citizen of the United States, residing at Glenside, Montgomery county, State of Pennsylvania, have invented a certain new, original, and ornamental Design for a Bracket Wall-Plate, of which the following is a specification, reference being had to the accompanying drawing, forming part thereof.

Figure 1 is a plan view of a bracket wall

plate, showing my new design; the ornamentation being shown below the section line and the type of ornamentation above the line being identically the same; and Fig. 2 is a side elevation thereof.

I claim:—

The ornamental design for a bracket wall plate, as shown.

WILLIAM HORN.

Witness:

ALEXANDER PARK.
